UNITED STATES PATENT OFFICE.

PARK TERRELL, OF MONTCLAIR, NEW JERSEY, ASSIGNOR TO COLUMBIA TRUST COMPANY, OF NEW YORK, N. Y., A CORPORATION OF NEW YORK.

DESIGN FOR A FONT OF TYPE.

No. 39,238.

Specification for Design.

Patented March 31, 1908.

Application filed December 24, 1907. Serial No. 407,967. Term of patent 14 years.

To all whom it may concern:

Be it known that I, PARK TERRELL, a citizen of the United States, residing at Montclair, in the county of Essex and State of New Jersey, have invented a new, original, and ornamental Design for Font of Printing-Type, of which the following is a specification, reference being had to the accompanying drawing, forming part thereof.

Generally speaking, my design for a font of type is Gothic or of Gothic effect, of medium weight, without ornament, with no curved lines, and all of the lines being of uniform weight except where the horizontal top lines join the right-hand side of the perpendicular

lines in the lower case letters "h", "m", "n", and "r", such connecting lines being of lighter weight, and except also, where short diagonal lines are employed in the figures 5, 6 and 9, as shown in the drawings. The serifs employed in my design are as shown, very small and pointed.

What I claim is:—

The ornamental design for a font of type, as shown and described.

PARK TERRELL.
